UNITED STATES PATENT OFFICE.

HARVEY S. MARSH, OF BASS RIVER, CANADA, ASSIGNOR OF ONE-HALF TO
DAWSON JOHNSON, OF BOSTON, MASSACHUSETTS.

DOWEL.

SPECIFICATION forming part of Letters Patent No. 475,407, dated May 24, 1892.

Application filed July 6, 1891. Serial No. 398,521. (No model.)

To all whom it may concern:

Be it known that I, HARVEY S. MARSH, of Bass River, in the county of Colchester, Nova Scotia, Dominion of Canada, have invented 5 certain new and useful Improvements in Dowels, of which the following is a description sufficiently full, clear, and exact to enable any person skilled in the art or science to which said invention appertains to make and use the same, reference being had to the accompanying drawings, forming part of this specification, in which—

Figure 1 is an elevation of my improved dowel; Fig. 2, a like view showing an alternative arrangement; Fig. 3, a cross-section taken on line *xx* in Fig. 2, showing the groove or thread; Fig. 4, a like view taken on line *yy*, showing the locking-teeth or serrations; and Fig. 5, an elevation showing modification in 20 the formation of the thread; and Fig. 6, a cross-section taken on line *zz* in Fig. 5.

Like letters of reference indicate corresponding parts in the different figures of the drawings.

25 My invention relates especially to a double screw, which is adapted to be employed for doweling purposes, and a locking device therefor; and it consists in certain novel features hereinafter fully set forth and claimed, the 30 object being to produce a simpler, cheaper, and more effective device of this character than is now in ordinary use.

The nature and operation of the improvement will be readily understood by all conversant with such matters from the following 35 explanation:

In the drawings, *A* represents the dowel considered as a whole, said dowel being constructed from a metallic rod, the center portion *d* of which is toothed peripherally, forming a locking device. From said center portion the dowel is provided with a longitudinally-oblique groove in each direction, the portion *f* being grooved in diametrically-opposite 40 direction from the corresponding portion *g* at the opposite side of the serrated portion. The guide-points *h* on the screws thus formed are rounded and slightly reduced in diameter from the body of the dowel, the ends of the groove-walls *i* being beveled at *j* until flush with said 45 guides.

In the use of my improvement the parts to be doweled together are bored or tapped in the ordinary manner when a smooth dowel-pin is used. The guide-points *h* are then inserted in 55 the openings thus formed and said parts driven by clamps or other suitable mechanism onto the dowel. The grooves of the parts *g f* running in opposite directions, the dowel *A* is caused to rotate, feeding gradually into the 60 dowel-holes. The pitch of the teeth *d* is in direction opposite that of the rotation of the dowel, so that when the parts being connected reach said serrated portion it will turn freely 65 therein until the parts are brought into contact. Said parts of bodies being moved to separate them would cause the dowel to tend to rotate in the opposite direction, in which event the teeth *d* would take in the material of said bodies, locking the dowel against such rotation and preventing accidental displacement 70 thereof.

Instead of the guide-points *h* the dowel may be furnished with gimlet-threaded points, the grooves of which gradually broaden to the 75 grooves of the portions *f g*.

In Fig. 2 the serrated portion is shown disposed eccentrically, this form being employed when bodies which are of a different degree of hardness are being doweled together, the 80 longer side *g* in this case being employed for the softer material and advancing more easily therein. The groove-walls of the portions *fg* may be notched or spurred at *m* on their edges, as shown in Fig. 5, said spurs inclining 85 obliquely to the line of motion of the dowel, so that they do not interfere with the insertion of the dowels in the bodies, but lock the same against being withdrawn. In this form the serrated portion *d* is not used, as said 90 spurs serve the same purpose to prevent the withdrawal of the dowel.

One part, as *g*, may be omitted from the dowel and the remainder be employed as an ordinary lag-screw, the portion *d* forming the 95 shank thereof and preventing its being turned out from the material.

Having thus explained my invention, what I claim is—

1. A metallic dowel having a portion of its 100 body toothed peripherally, the ends of said body at opposite sides of said tooth portion

being respectively provided with longitudinally-oblique grooves running in opposite directions, substantially as and for the purpose set forth.

5. 2. A metallic dowel having a portion of its body toothed peripherally, the remainder of said body being provided with longitudinally-oblique grooves, substantially as specified.

3. A metallic dowel having its body provided with longitudinally-oblique grooves running in opposite directions from the center thereof, the walls of said grooves being notched or serrated, substantially as described.

4. The dowel A, provided with the serrated portion d and grooved portions f g, arranged to operate substantially as described.

5. The dowel A, having the serrated portion d, grooved portions f g, beveled at j, and the guide-points h, arranged to operate substantially as specified.

HARVEY S. MARSH.
